UNITED STATES PATENT OFFICE.

OMAR E. CLARK, OF DENVER, COLORADO, ASSIGNEE TO THE DENVER ROCK DRILL MANUFACTURING COMPANY, OF DENVER, COLORADO, A CORPORATION OF DELAWARE.

ROCK-DRILL

1,183,274.

Specification of Letters Patent. Patented May 16, 1916.

Application filed September 30, 1914. Serial No. 864,251.

To all whom it may concern:

Be it known that I, OMAR E. CLARK, a citizen of the United States, residing at Denver, in the county of Denver and State of Colorado, have invented new and useful Improvements in Rock-Drills, of which the following is a specification.

The present invention relates to rock drills, in which means are provided for delivering a cleansing agent to the bore of the drill bit, and thus to the bottom of the drill hole for removing the cuttings from the latter.

One of the principal objects is to provide a novel and effective mechanism for supplying both a liquid and a gaseous cleansing agent, either or both of which may be used as desired.

In drilling, it is a well known fact that a predetermined supply of air or gaseous cleansing agent is sufficient for normally blowing out the dust, but that often the detritus becomes packed around the drill bit, and if allowed to accumulate, will cause the drill to become stuck. In such an event, it is highly desirable to augment the supply of cleansing agent in order to remove the accumulation, and an important feature of this invention is the provision of means whereby the desired additional supply is automatically obtained by the natural and practically involuntary movements of the operator in his efforts to release the drill bit.

The preferred embodiment of the invention is illustrated in the accompanying drawings, wherein:—

Figure 1 is a longitudinal sectional view through the drill, illustrating the piston at the forward end of its normal stroke. Fig. 2 is a similar view, with the piston abnormally advanced. Fig. 3 is a rear elevation of the rear cylinder head, with portions illustrated in section. Fig. 4 is a detail view on the line 4—4 of Fig. 3. Figs. 5 and 6 are cross sectional views respectively on the lines 5—5 and 6—6 of Figs. 1 and 2. Fig. 7 is a cross sectional view on the line 7—7 of Fig. 1. Fig. 8 is a detail perspective view of the liquid-conducting tube.

Similar reference numerals designate corresponding parts in all the figures of the drawings.

In the embodiment disclosed, a cylinder member 9 is employed, in which is located a

reciprocating piston 10 having a reduced extension 11 that operates on a drill bit 12 located in a chuck 13 carried by the front end of the cylinder member and having a bore 14 through which the cleansing agent or agents are conducted to the bottom of the drill hole. The piston, in the embodiment illustrated, is of the valveless type, and has an internal constant pressure chamber 15, which is supplied with fluid under pressure through a tubular member 16 that snugly fits in the rear end thereof, said end being slidable on said tube, and said tube constituting a part of the rear head 17. Fluid under pressure from any suitable source is conveyed by a conduit, not shown, to a nipple 18 containing a throttle valve 19, and this nipple has communication, as indicated at 20, with the bore of the tubular member 16. The fluid is distributed from the chamber 15 of the piston alternately to opposite ends 75 of said piston by ports 21 formed in said piston, said ports being controlled by the walls of the cylinder member 9. No claim is herein made to this structure, as the same constitutes the subject-matter of a co-pending application, Serial No. 875,465, and it is therefore believed to be unnecessary to go into detail in so far as the operation of the piston is concerned, it being understood that as said piston is reciprocated, it will deliver 85 blows against the drill bit 12. The said piston and its extension is provided with a longitudinal axial bore 22 extending from the front end of the constant pressure chamber 15, through the front end of the extension 11, and thus being in communication with the bore 14 of the drill bit 12. This bore preferably has a reduced rear end 23. A tube for conducting cleansing liquid to the drill bit is shown at 24, said tube having 95 its rear end suitably mounted in the rear head of the cylinder member. In the preferred form of construction, this is accomplished by forming a socket 25 in said head, in which socket the rear end of the tube 24 is received, said end being preferably flanged, as shown at 26. A packing gasket 27 is placed in the socket in advance of the flange, and is clamped thereagainst by a plug nut 28. Liquid is supplied to the rear 100 end of the tube from any suitable source, through a nipple 29 having a port 30 that communicates with the tube. This tube, as

shown, extends axially through the tubular supply member 16, through the constant pressure chamber 15 and into the bore 22. Its cross sectional area is less than said bore 22 and also less than the reduced portion 23. It will thus be seen that fluid in the constant pressure chamber 15 can flow through the bore 22-23 around the tube 24, and thus gain access to the bore 14 of the drill bit. 10 It will be noted that the front portion of the tube has its exterior faces cut away or channeled, as shown at 31, so that this portion is of less cross sectional area than the rear portion. These channels 31, however, terminate 15 at their rear ends at a point on the tube that is not located in the constant pressure chamber 15 when the piston 10 is at the end of its normal working stroke, as shown in Fig. 1. The piston 10, however, has a variable stroke. For example, if the drilling machine is lifted slightly with respect to the drill bit, so that said drill bit does not extend into the chuck to the normal position shown in Fig. 1, then, as illustrated in Fig. 25 2, the piston has a longer stroke which is sufficient to expose the rear ends of the channels 31 in the constant pressure chamber 15. As a result of this arrangement, while there is always a limited flow of fluid 30 from the constant pressure chamber around the tube 24 to the drill bit, a greatly increased flow occurs when the parts operate as illustrated in Fig. 2.

Briefly described, the operation of the apparatus is substantially as follows: Assuming that the fluid under pressure is being supplied through the tubular member 16 to the constant pressure chamber 15, this fluid is distributed through the ports 21, a portion of it thus becoming the actuating fluid for the piston. A portion, however, becomes the cleansing fluid that escapes through the bore 23-22 to the drill bit. If water or a liquid cleansing agent is desired, 45 it is only necessary to admit the same through the tube 24, whereupon it will be projected in a stream from the reduced front end of the tube into the rear end of the drill bit, the surrounding column of air or 50 fluid under pressure confining it and insuring its escape into said drill bit. Under ordinary working conditions, it will be understood that the machine is held pressed against the work, so that the rear end of 55 the drill bit 12 is disposed well within the chuck, and the piston will strike its blow and return without the rear ends of the channels 31 entering the constant pressure chamber. If, however, there is an accumulation 60 of dust or cuttings around the drill bit, the natural thing for the operator to do is to move the machine back and forth, the drill bit being held to the machine by any of the well known devices. In this 65 loosening action of the operator, the drill

bit thus is advanced in the chuck, and consequently the piston advances farther before striking its blow. As a consequence the rear ends 31 of the channels are uncovered, as shown in Fig. 2, and a large volume of 70 fluid at initial pressure is thus forced through the drill bit.

From the foregoing, it is thought that the construction, operation and many advantages of the herein described invention will 75 be apparent to those skilled in the art, without further description, and it will be understood that various changes in the size, shape, proportion and minor details of construction may be resorted to without departing from the spirit or sacrificing any 80 of the advantages of the invention.

Having thus fully described my invention, what I claim as new, and desire to secure by Letters Patent, is:-

1. In drilling apparatus of the character set forth, the combination with a cylinder member, of a piston operating therein and having an internal constant pressure chamber, means for distributing fluid from said chamber to operate the piston, and means for delivering fluid from said constant pressure chamber to the bore of a drill bit operated on by the piston, for cleansing the 90 drill hole.

2. In drilling apparatus of the character set forth, the combination with a cylinder member, of a piston operating therein and having an internal constant pressure chamber, means for distributing fluid from said chamber to operate the piston, and a conduit formed in the piston and leading from the constant pressure chamber, said conduit communicating with the bore of a drill bit operated on by the piston for delivering 100 cleansing fluid thereto.

3. In drilling apparatus of the character set forth, the combination with a cylinder member having a front drill-receiving chuck, of a drill bit that engages therein, 110 said bit having a bore for cleansing fluid, a piston operating in the cylinder member and having an internal constant pressure chamber, means for delivering fluid from the chamber to operate the piston, and a conduit formed in the piston for conveying fluid from the constant pressure chamber to the bore of the drill bit.

4. In drilling apparatus of the character set forth, the combination with a cylinder 120 member having a front drill-receiving chuck, of a drill bit that engages therein, said bit having a bore for cleansing fluid, a piston operating in the cylinder member and having an internal constant pressure 125 chamber, ports leading from the constant pressure chamber and delivering fluid alternately to opposite ends of the piston to actuate the same, and a conduit extending from the pressure chamber through the 130

front end of the piston for conveying fluid from said chamber to the bore of the drill bit.

5. In drilling apparatus of the character set forth, the combination with a cylinder member, of a piston operating therein and having an internal constant pressure chamber, means for delivering fluid from said constant pressure chamber to the bore of a drill bit operated on by the piston for cleansing the drill hole, and means in the piston for varying the amount of fluid so delivered.

6. In drilling apparatus of the character set forth, the combination with a cylinder member, of a piston operating therein and having an internal constant pressure chamber, a conduit formed in the piston and leading from the constant pressure chamber, said conduit communicating with the bore of a drill bit operated on by the piston for delivering cleansing fluid thereto, and means for varying the effective cross sectional area of the conduit to vary the amount of fluid delivered therethrough.

7. In drilling apparatus of the character set forth, the combination with a cylinder member and a piston operating therein and having a variable stroke, of a conduit in the piston to deliver cleansing fluid to a drill bit operated on thereby, and means for controlling the conduit by the varied stroke of the piston to vary the amount of cleansing fluid delivered therethrough.

8. In drilling apparatus of the character set forth, the combination with a cylinder member and a piston operating therein and having a variable stroke, of a conduit formed in the piston to deliver cleansing fluid to a drill bit operated on thereby, and a device located in said conduit and adapted to vary the amount of cleansing fluid delivered when the stroke of the piston varies.

9. In drilling apparatus of the character set forth, the combination with a cylinder member and a piston operating therein, of a conduit formed in the piston to deliver cleansing fluid to a drill bit operated on thereby, a device carried by the cylinder member and projecting into the conduit, said device having portions of different cross sectional areas, and means for varying the stroke of the piston and thereby exposing different portions of said device to vary the amount of cleansing fluid delivered to the conduit.

10. In drilling apparatus of the character set forth, the combination with a cylinder member and a piston operating therein and capable of a variable stroke, of means controlled by said variable stroke of the piston for delivering different amounts of cleansing fluid to a drill bit operated on by the piston.

11. In drilling apparatus of the character set forth, the combination with a cylinder

member and a piston operating therein and capable of a variable stroke, said piston having an internal chamber and a bore leading therefrom for delivering cleansing fluid to a drill bit operated on by the piston, of a device mounted on the cylinder member and projecting into the bore, said device having portions of different cross sectional areas that are respectively exposed on the different strokes of the piston to vary the amount of cleansing fluid delivered to the drill bit.

12. In drilling apparatus of the character set forth, the combination with a cylinder member and a piston operating therein, of means passing through the piston for introducing a liquid cleansing agent into a drill bit operated on by the piston, and means formed in the piston and moving with it for securing a supply of gaseous cleansing agent under constant pressure and delivering the same to said drill bit.

13. In drilling apparatus of the character set forth, the combination with a cylinder member and a piston operating therein, of a tube passing through the piston for introducing a liquid cleansing agent into a drill bit operated on by the piston, a bore in the piston constituting a conduit for directing a gaseous cleansing agent to said drill bit, and means for supplying such gaseous agent under constant pressure to the bore.

14. In drilling apparatus of the character set forth, the combination with a cylinder member and a piston operating therein and having an internal constant pressure chamber and a bore extending therefrom for conducting cleansing fluid from the chamber to a drill bit operated on by the piston, of a tube extending through the constant pressure chamber and bore for delivering a cleansing agent to said drill bit and having a smaller cross sectional area than the bore to permit the passage of fluid therethrough.

15. In drilling apparatus of the character set forth, the combination with a piston having an internal constant pressure chamber, of means for delivering fluid under pressure to said chamber, means formed in the piston for distributing said fluid alternately to opposite ends of the piston for actuating the same, said piston having an axial bore extending from the constant pressure chamber to the front end of the same and constituting a conduit for delivering a cleansing fluid from the chamber to a drill bit operated on by the piston, and a fluid conducting tube extending through the supply means for the constant pressure chamber and through the bore, said tube being of less cross sectional area than the bore.

16. In drilling apparatus of the character set forth, the combination with a piston, of means formed in the piston for creating a body of fluid under constant pressure therein and continuously passing a portion of

such fluid therethrough to a drill bit operated on by the piston, and a tube extending through the piston for delivering a cleansing agent to the said drill bit, said tube constituting means for controlling the amount of fluid passing through the piston by the first-mentioned means.

17. In drilling apparatus of the character set forth, the combination with a piston, of a bore in the piston, constituting a conduit for passing fluid therethrough to a drill bit operated on by the piston, a tube extending through the piston for delivering a cleansing agent to such drill bit, said tube having portions of different cross sectional area, and means for exposing different portions to permit varying amounts of fluid to pass through said bore around the tube.

18. In drilling apparatus of the character set forth, the combination with a cylinder member, of a reciprocatory piston operating therein and having an internal constant pressure chamber, a tubular supply member projecting forwardly into the constant pressure chamber, ports leading from said pressure chamber and alternately delivering to opposite ends of the piston for actuating the same, said piston having an axial bore extending from the constant pressure chamber to its front end for delivering cleansing fluid from the chamber to a drill bit operated on by the piston, and a tube extending longitudinally through the supply member, the constant pressure chamber and the bore for delivering a cleansing agent to said drill bit, said tube having its front portion of less cross sectional area than its rear portion, and the tube furthermore being of less

cross sectional area than the bore to permit the passage of the cleansing agent through said bore around the tube, said piston having a variable stroke and uncovering the portion of the tube having the smaller cross sectional area in the constant pressure chamber only when on its longer stroke.

19. In drilling apparatus of the character set forth, the combination with a cylinder member and a piston operating therein and having an internal chamber, of means for delivering cleansing fluid from the chamber to the bore of a drill bit operated on by the piston, and a device extending into the chamber for controlling the amount of cleansing fluid discharged therefrom through said delivering means.

20. In drilling apparatus of the character set forth, the combination with a cylinder member and a piston operating therein and having an internal chamber, of means for delivering cleansing fluid from the chamber to the bore of a drill bit operated on by the piston, said means including a discharge port extending from the front end of the chamber, and a device extending into the rear end of the piston and into the chamber, the front end of said device coöperating with the discharge port to control the amount of cleansing fluid discharged there-through.

In testimony whereof I have hereunto set my hand in presence of two subscribing witnesses.

OMAR E. CLARK.
